RECEPTACLE FOR SMOKERS' ARTICLES

Max Hackman, Brooklyn, N. Y.

Application December 12, 1936, Serial No. 115,484

11 Claims. (Cl. 131—51)

This invention relates to receptacles for smokers' articles, for receiving and housing such items as pipes, cigars, cigarettes, tobacco, pipe cleaners, matches, tobacco ashes, etc.

Receptacles of this class, frequently referred to as "Smokadors", are commonly adapted to contain only a very limited number of smokers' articles, unless the device is made unduly large,—and such devices are generally difficult to clean of accumulations of tobacco and ash particles. It is hence one of the objects of my invention to eliminate these shortcomings in a device of this class by providing a compact and presentable receptacle of simple construction, that will conveniently accommodate a large variety of smokers' articles, and that can be readily cleaned.

It is also within the contemplation of this invention to permit of the sanitary housing of a plurality of pipes of various sizes, with their bowls down, and to enable the ready and convenient positioning of pipes in place and their withdrawal therefrom.

And another object of my invention is to enable a portion of the structure to be adapted for other purposes and uses, if desired, apart from its principal use as above set forth.

Other objects, features and advantages will appear from the drawing and the description hereinafter given.

30 In the drawing,

Figure 1 is a perspective view of the device constituting my invention, illustrating various smokers' articles in place, part of the central tobacco jar cover being shown broken away.

35 Figure 2 is a plan view of the device of Figure 1, the central tobacco jar and cover and the various smokers' articles being removed.

Figure 3 is a vertical transverse section of Figure 2 taken along line 3—3, the removable insert being shown by dot-dash lines in a partly elevated position.

40 Figure 4 is a vertical transverse section of Figure 2 taken along line 4—4, and

45 Figure 5 is a fragmentary sectional plan taken along line 5—5 of Figure 4.

Referring to the drawing, the casing 6, which constitutes the outer framework of this device, is open at the top and preferably closed at the bottom by the base 7. The casing, which in the 50 form illustrated in the drawing is octagonal, contains the spaced lateral panels 8, 9, 10 and 11 positioned between and attached to the upper and lower peripheral frames 12 and 12' respectively, the said panels being preferably positioned at alternate sides of the polyhedron.

Proportioned so as to operatively fit the interior of the casing 6 is the insert 13 consisting essentially of a top member 14, a base 15 and a number of recessed compartments each formed by the said member 14 and base 15 and three vertical walls therebetween. In the form illustrated, there are four of such compartments to correspond with the octagonal shape of the casing, the walls 17, 18 and 19 forming an alcove 18a between panels 11 and 8, the walls 20, 21 and 22 forming the alcove 29 between panels 8 and 9, the walls 23, 24, and 25 forming the alcove 30 between panels 9 and 10, and the walls 26, 27 and 28 forming alcove 31 between panels 10 and 11. Although in the preferred arrangement the walls 17, 19, 20, 22, 23, 25, 27 and 28 are substantially radially disposed with respect to the polyhedron shown, they can be otherwise arranged and designed within the intent of this invention.

The said top member 14 contains a number of apertures and recesses therein which cooperate with the said alcoves and panels to form suitable compartments and retaining members for various smokers' articles, as will more fully hereinafter appear. The apertures 32, 33, 34, 35, 36, 37, 38 and 39 are positioned above the aforementioned recessed compartments forming the said alcoves, the walls thereof serving as retaining members for the stems of the inverted pipes positioned within the alcoves. The recesses 40 and 41 are for accommodating cigarettes and cigars, preferably within supporting receptacles 42 and 43 suitably attached to the underside of the member 14 and in registry with the said recesses. The aperture 44 is for receiving the ash tray 45, which is preferably suspended from the walls of said aperture by the flange 46. It should be noted that in order to properly accommodate the ash tray, the upper portion of the walls 17 and 28 are cut away. Underneath the said ash tray is a bin 47 formed by the vertical wall 48 and the two side walls 17 and 28,—this bin being for the storage of miscellaneous small articles. The member 14 also contains the recess 49 for accommodating pipe cleaners, preferably within a supporting receptacle 50 suitably attached to the underside of member 14 and in registry with recess 49. The elevated support or lug 51 positioned on the upper surface of member 14 is adapted to support a box of matches in conventional manner. And the central aperture 52 is for receiving therethrough a tobacco jar 53 adapted to rest on the base 15,—the cover 54 being of the conventional type with a sponge or other humidifying element therein.

It is thus apparent that upon a proper positioning of the insert 13 within the casing 6, the component parts of these structures cooperate to produce compartments and supports for various smokers' items. The said insert 13 with its attached parts is an independently fabricated unit which, without any further steps than that of simply inserting it in place, forms together with the casing a completely assembled device ready for use. Alcoves for the pipes are formed by the top and bottom of the insert 13, the vertical walls thereof, and the open portions of the casing between the panels thereof,—in cooperation with the holes for the pipe stems; the cigarette, cigar, pipe cleaners and ash receiving portions of this device are formed by recesses and apertures in the top member of the insert 13 and the panels of the casing 6; the receptacle for the tobacco jar is formed by the combination of the top member of insert 13 and the interior of casing 6; and the said bin 47 is formed by the combination of certain walls on the insert 13 and a panel on casing 6.

Certain of the alcoves can be provided with a horizontal floor such as 55 to accommodate pipes with short stems, the bowls of which will rest upon such floors. The position of floor 55 may be at any suitable level between the top member 14 and the base 15.

It should also be noted that although a solid base 7 is illustrated in the drawing, this base can be of any desired, either open or solid, configuration, inasmuch as its prime purpose is to support the insert 13.

Should there be an accumulation of tobacco or ash dust within the device, all that need be done is to remove the insert, and simply shake it and the casing 6 clean. And inasmuch as the said casing 6 contains lateral openings, access to the interior thereof for further cleaning can also be readily had.

It is a generally recognized fact that pipes should be housed inverted, that is, with the bowls down. Where pipes are positioned within the interior of a casing, their insertion generally presents some difficulty, as they are usually inserted through a central opening. In the structure of my invention, however, the pipes are protected within an alcove, and yet readily insertable from the outside.

It should be noted that when the insert 13 is removed, the casing 6 constitutes an article that has independent utility, such as that of a container and receptacle for sundry articles to which ready access can be had through the openings between the panels.

It is of course understood that the various embodiments above described and shown in the drawing are illustrative of my invention and not employed by way of limitation, inasmuch as numerous changes and modifications may be made within the scope of the appended claims without departing from the spirit of this invention.

What I claim is:

1. In a receptacle for smokers' articles, a hollow casing open at the top and having apertures in the lateral wall thereof, and an insert removably positioned within the casing and suitably supported thereby, said insert containing a top member extending substantially across the top of the casing and having therein a plurality of holes communicating with underlying regions directly behind said apertures and adapted to receive therethrough the upwardly extending

stems of pipes located in said regions, and supports for the bowls of said pipes.

2. In a receptacle for smokers' articles, a hollow casing having a plurality of spaced apertures in the lateral wall thereof, a base and a top member, and vertical walls behind said apertures and between said base and top member forming a plurality of spaced inwardly extending alcoves, the said top member containing a plurality of holes communicating with said alcoves. 10

3. In a receptacle for smokers' articles, a hollow casing open at the top and having apertures in the lateral wall thereof, and an insert removably positioned within the casing and suitably supported thereby, said insert containing a top member extending substantially across the top of the casing and a plurality of vertical walls below said top member, said walls forming a plurality of laterally open compartments in registry with the said apertures to form inwardly extending alcoves, and the said top member containing a plurality of holes communicating with said alcoves. 15

4. In a receptacle for smokers' articles, a hollow polyhedral casing open at the top, certain of the sides of the lateral wall of the casing being removed to form apertures therein, and an insert removably positioned within the casing and suitably supported thereby, said insert containing a top member and a base extending across the top and the bottom of the casing respectively, and said top member having therein a plurality of holes communicating with underlying regions directly behind said apertures. 30

5. In a receptacle for smokers' articles, a hollow polyhedral casing open at the top, certain of the sides of the lateral wall of the casing being removed to form apertures therein, and an insert removably positioned within the casing and suitably supported thereby, said insert containing a top member extending substantially across the top of the casing and a plurality of vertical walls below said top member, said walls forming a plurality of laterally open compartments in registry with the said apertures to form inwardly extending alcoves, and the said top member containing a plurality of holes communicating with said alcoves. 40

6. In a receptacle for smokers' articles, a hollow casing open at the top and having apertures in the lateral wall thereof, peripheral frames at the top and bottom of the casing respectively and supporting the lateral wall thereof, a base secured to the frame at the bottom of the casing, and an insert removably positioned within the casing and supported by said base, said insert containing a top member extending substantially across the top of the casing substantially at the level of the upper frame and having therein a plurality of holes communicating with underlying regions directly behind said apertures. 50

7. In a receptacle for smokers' articles, a hollow casing open at the top and having apertures in the lateral wall thereof, and an insert removably positioned within the casing and suitably supported thereby, said insert containing a top member extending substantially across the top of the casing and having therein a plurality of holes and peripheral recesses, said holes communicating with the underlying regions directly behind said apertures, and said recesses communicating with underlying regions directly behind the portions of the said lateral wall without apertures therein. 65

8. In a receptacle for smokers' articles, a hollow casing open at the top and having apertures in the lateral wall thereof, peripheral frames at the top and bottom of the casing respectively and supporting the lateral wall thereof, a base secured to the frame at the bottom of the casing, and an insert removably positioned within the casing and supported by said base, said insert containing a top member extending substantially across the top of the casing substantially at the level of the upper frame and having therein a plurality of holes and peripheral recesses, said holes communicating with the underlying regions directly behind said apertures, and said recesses being adjacent the said upper frame and forming therewith laterally enclosed openings, said openings communicating with underlying regions directly behind the portions of the said lateral wall without apertures therein.
9. In a receptacle for smokers' articles, a hollow casing open at the top and having apertures in the lateral wall thereof, and an insert removably positioned within the casing and suitably supported thereby, said insert containing a top member and a base extending across the top and bottom of the casing respectively, and a plurality of sets of three adjacent vertical walls between said top member and base, each set forming a compartment in registry with one of said apertures to form inwardly extending alcoves, the said top member containing a plurality of holes and peripheral recesses, certain of said holes communicating with said alcoves, another of said holes being centrally disposed on the top member and communicating with the interior of the casing and being adapted to receive therethrough a container, the said base and circumferential wall of the central hole cooperating to hold said jar in place, and the said recesses communicating with underlying regions directly be-
- hind the portions of the said lateral wall without apertures therein.
10. In a receptacle for smokers' articles, a hollow casing open at the top and having apertures in the lateral wall thereof, and an insert removably positioned within the casing and suitably supported thereby, said insert containing a top member extending substantially across the top of the casing and having therein a plurality of holes and peripheral recesses, said holes communicating with the underlying regions directly behind said apertures, and said recesses communicating with underlying regions directly behind the portions of the said lateral wall without apertures therein; and open-topped receptacles suspended from the underside of said top member and in registry with certain of said recesses, each of said receptacles being open at its outer lateral side and adjacent the said lateral wall to form a laterally enclosed container.
11. In a receptacle for smokers' articles, a hollow casing open at the top and having apertures in the lateral wall thereof, and an insert removably positioned within the casing and suitably supported thereby, said insert containing a top member extending substantially across the top of the casing and a plurality of vertical walls below said top member, said walls forming a plurality of laterally open compartments in registry with the said apertures to form inwardly extending alcoves, the said top member containing a plurality of holes certain of which communicate with said alcoves, a flanged receptacle extending through another of said holes and suspended from the wall thereof, and a horizontal floor extending transversely across one of said alcoves intermediate the bottom of the casing and said top member.

MAX HACKMAN. 40
